UNITED STATES PATENT OFFICE.

ERNEST W. SEAHOLM, OF DETROIT, MICHIGAN, ASSIGNOR TO GENERAL MOTORS CORPORATION, OF DETROIT, MICHIGAN, A CORPORATION OF DELAWARE.

RADIATOR CAP.

Application filed November 15, 1926. Serial No. 148,540.

This invention relates to radiators for automobiles and more particularly to the filler opening or spout leading to the radiator core.

It is the practice to enclose the radiator core within a housing or shell of more or less pleasing appearance, and to extend the radiator filler spout upward thru the top of the housing. Among the objects of the present invention, is the provision of a novel closure for the filler opening and to further provide the regular radiator housing opening with a flange around the radiator spout, which will combine with the closure cap in lending ornamentation to the filler opening.

15 A further object is to provide a simple and efficient means for fastening the flange to the radiator casing and to utilize a portion of the flange as a pivotal mounting for the engine hood.

20 Other incidental objects will appear from the following specification and accompanying drawing, showing the preferred but not necessarily, the only form of the invention, wherein Figure 1 is a vertical sectional view of a radiator filler opening embodying the present invention. Figure 2 is a front elevation thereof; Figure 3 is a top plan view of the radiator housing flange for the spout opening and Figure 4 is an enlarged detail view showing an attachment lug on the flange.

Fragmentarily shown at 1 and 2 are the upper portions of a radiator and the housing or casing respectively. Extending upwardly from the radiator inlet chamber, is the filling spout or tube 3, having an interiorly threaded sleeve 4, fitted in its top. For economy of manufacture, the closure cap 5, may be die cast, with a seamless tube insert 6, of brass or other suitable material, having exterior screw threads for engagement with the filler spout sleeve 4. Thus the cap may be made comparatively shallow in depth with a clear space at the center for fastening a cap ornament, or a temperature indicator, as is shown in dotted lines. A downwardly depending flange at the periphery of the closure cap, forms with the tube 6, an annular groove in which is seated a packing ring or gasket 7, to rest on the edge of the filler spout.

At the spout opening in the radiator cas-

ing, is the flange or shell 8, which like the closure cap, may be a die casting. A preferred form of securing the spout or flange 8, to the casing 2, is to form several integral posts or lugs 9, on the undersurface of the shell, in the nature of rivets, which are expanded or flattened in holes or openings in the radiator casing. A rearwardly projecting hollow boss 10, may also be cast with the shell to provide a bearing for the engine hood hinge rod, as illustrated by the dotted lines in Figure 1. The shell 8, surrounding the filler spout, extends into the annular groove on the bottom of the cap 5 and the shell and cap are preferably provided with surface contours, of any desired combination, to co-operate with each other in presenting an ornamental finish of pleasing effect to the radiator filler opening.

While the invention has been described more or less specifically, it is to be understood, that such modifications may be made as come within the scope of the appended claims.

Having described the invention, I claim:

1. In a filler opening, in combination, a filling spout, an ornamental shell surrounding the spout, and an ornamental closure cap having a dependent portion detachably engageable with the interior of the spout and provided with an annular groove into which the upper portion of the shell extends, whereby the ornamental contours of the cap and shell are combined in cooperative relation.

2. In a filler opening, in combination, a spout, a closure cap therefor, having a dependent peripheral flange, and an inner dependent portion spaced from the peripheral flange affording therebetween, an annular groove, said dependent portion having screw threaded engagement with the interior of the spout, a packing gasket carried within the annular groove to rest on the top of the spout, and a shell surrounding the spout and extending into said groove.

3. In a radiator filler opening, in combination, a radiator casing, a filler spout projecting thru the casing and a shell for the spout having integral downwardly projecting rivet lugs for fastening attachment to the radiator casing.

4. In a radiator filler opening, in combina-

tion, a filling spout, a cast metal shell surrounding the spout, but independent thereof, and having cast integrally therewith, a rearwardly projecting hollow boss for the engine hood hinge rod and dependent lugs for attachment to the radiator casing, and a detachable closure cap for the spout co-operating with said shell to afford a finish to the filler opening.

5. In a radiator filler opening, the combination with a radiator casing and a filling spout, of a decorative shell for the spout having integral dependent rivet lugs extended and expanded in openings in the radiator casing to secure the shell in place. 10 15

In testimony whereof I affix my signature.

ERNEST W. SEAHOLM.
